TOY RAILWAY

Original Filed July 22, 1922

Inventor.
A. R. Ferguson
by his Attorneys,
Weed Gray

UNITED STATES PATENT OFFICE.

ALAN R. FERGUSSON, OF BUFFALO, NEW YORK.

TOY RAILWAY.

Original application filed July 22, 1922, Serial No. 576,656. Patent No. 1,457,771, dated June 5, 1923.
 Divided and this application filed April 5, 1923. Serial No. 629,960.

To all whom it may concern:

Be it known that I, ALAN R. FERGUSSON, a citizen of the United States, residing at Buffalo, in the county of Erie and State of New York, have invented certain new and useful Improvements in Toy Railways, of which the following is a specification.

This invention relates to toy tracks or toy railways, and is a division of my co-pending application for a toy railway, filed July 22, 1922, Serial No. 576,656, which is issued in Patent No. 1,457,771, June 5, 1923.

An object of this invention is to provide an improved toy railway structure which will be strong, durable and serviceable in use and yet which, by virtue of the present novel structure may be constructed at a minimum of expense.

A further object of this invention is to provide a sectional toy railway wherein the ends of the rails of the several sections may be quickly and efficiently joined and held in alinement in an improved manner, in the present instance this being obtained by the formation of substantially a resilient or spring joint.

A further object of this invention is to provide a toy railway having wire formed rails, and wherein the side faces of the wire rails are rolled out to form inwardly extending concave faces, this construction increasing the height of the rails without at the same time requiring a larger wire or more material, and also enabling the juxtaposed ends of a pair of rails to be readily connected together by means of connecting members extending into concave faces of the rails.

Other objects of this invention will appear in the following description and appended claims, reference being had to the accompanying drawings forming a part of this specification wherein like reference characters indicate corresponding parts in the several views and wherein Fig. 1 is a plan view partly broken away illustrating my invention; Fig. 2 is an end sectional view of a wire rail; Fig. 3 is a fragmentary perspective view thereof; Fig. 4 is a perspective view of a form of filler or clamping block, Fig. 5 is a perspective view partly

in section illustrating a manner in which the juxtaposed ends of a pair of rails may be connected together; and Fig. 6 is a detail section illustrating the use of the form shown in Fig. 4.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

In the preferred form shown herein and described, the present invention in general preferably comprises a plurality of toy track sections adapted to be releasably joined together to form a complete railway, the sections being readily detached or released one from another to form a knock-down portable structure. Each section preferably comprises spaced wire formed ties and spaced wire formed rails secured to the ties as by spot welding. The juxtaposed ends of a pair of wire rails of adjacent sections are releasably connected together so as to form a tension or spring joint, this being accomplished in the present invention by means of an improved clamping device secured to one of the rails to form an extension thereof and adapted to be detachably connected to an adjacent rail.

Referring to Fig. 1 it will be seen that each of the adjacent track sections 9 and 10 comprises spaced wire formed ties 11, and mounted upon the several ties of each section are a pair of spaced wire formed rails 12. Each of the wire rails 12 in their original form is cylindrical and may be of any suitable gage or diameter. A pair of opposed convex side faces of each wire rail are rolled in any suitable manner so as to provide a pair of opposed grooved, channeled, or concave faces 13 and 14. The rolling of the concave faces 13 and 14 increases the height of the rails without at the same time requiring a larger wire or more material so that as a result of this construction, where it is necessary to provide a rail of a

given height, a wire of smaller diameter may be utilized, thus greatly decreasing the cost of manufacture.

It will be seen from the foregoing construction that each wire rail is provided with opposed concave faces 13 and 14, and with top and bottom curved or convex faces 15 and 16 which latter in the process of manufacture may be interchangeably used for the 10 connection of either of said faces to the ties. The convex face 15 also provides an effective traction surface for the wheels of the toy train.

In joining the free ends of a pair of juxtaposed rails 12, one pair of the rail ends as 15 may each be provided with a section or filler block 18 projecting beyond the end of the rail, and which block or clamping member may be formed by sawing in two a round 20 wire, or in any other suitable manner, so that the curved face 19 will fit into the concave or channeled side face of the end rail 17 as shown in Figs. 2 and 5. Referring to Figs. 4 and 6 it will be seen that the filler 25 block or clamp may be stamped or formed out of sheet metal so as to have a convex face 19 adapted to fit into the concave face 13. The segmental section 18^a or 18 as the case may be, is preferably spot welded at 30 to the rail end 17 and forms substantially a guide clamp adapted to releasably fit into the correspondingly formed concave or channeled face 21 of a juxtaposed rail end 22. The two rail ends 17 and 22 may be 35 releasably interlocked so as to prevent relative endwise movement through the medium of the filler block or clamp extension 18^a or 18. In the present instance the interlocking connection comprises a projection or lug 23 pinched or formed from the member 40 18 or 18^a and a notch or recess 24 formed in the rail end 22.

Thus it will be seen that in joining the 45 ends of the rails each rail end 17 may be tensioned or pressed inwardly to an extent sufficient to permit the lug 23 to clear the face 21 of rail end 22 and to spring into the recess 24 so as to become securely seated therein.

50 Thus it will be seen that the filler section 18^a or 18 forms substantially an extension of one of the rails 12 and the convex or segmental face 19 of this extension of one rail will extend into the concave face 21 of the 55 opposite rail, and the spring pressure of the rail ends, which is outwardly in this case insures the lateral alinement of the adjoining rail ends. The rail ends 17 of one track section may be readily and quickly released 60 from the rail ends 22 of the adjacent section merely by pressing inwardly one or both of the ends 17 sufficiently to withdraw the lugs 23 from the recesses 24 thereby permitting the rail ends 22 to be withdrawn 65 from the opposed rail ends. It will be noted

that the rail ends when joined in the foregoing manner will not accidentally become disconnected by one pair shifting upwardly out of engagement with the other due to the fact that the concave face 21 prevents 70 any relative upward movement of the convex face of member 18^a or 18.

It is to be understood that by describing in detail herein any particular form, structure, or arrangement, it is not intended to 75 limit the invention beyond the terms of the several claims or the requirements of the prior art.

Having thus explained the nature of my 80 said invention and described a way of constructing and using the same, although without attempting to set forth all of the forms in which it may be made, or all of the modes of its use, I claim:

1. In a toy railway a wire formed rail 85 having a lengthwise extending concaved face.
2. In a toy railway a wire formed rail having a lengthwise extending channeled side face.
3. In a toy railway a wire formed rail 90 having a pair of opposed longitudinally extending concaved faces.
4. In a toy railway a wire formed rail having a pair of opposed convex faces and a 95 pair of opposed concave faces.
5. In a toy railway a wire formed rail having a part of the metal thereof forced 100 inwardly to form a lengthwise extending groove.
6. In a toy railway a wire formed rail having a part of the metal thereof forced 105 inwardly to form a lengthwise extending groove, and a rail having a part cooperating with said groove.
7. In a toy railway a wire formed rail having a part of the metal thereof forced inwardly to form a lengthwise extending groove, and a rail having a part releasably 110 interlocked in said groove.
8. In a toy railway a pair of wire rails located end to end and having alined channeled faces, and means extending into said faces for releasably joining the rails together.
9. In a toy railway a pair of wire rails located end to end, and a block secured to 115 one rail and releasably connected to the other rail.
10. In a toy railway a pair of wire rails located end to end, one of said rails having an extension, and means for releasably connecting said extension to the other rail.
11. In a toy railway a pair of wire rails located end to end, one of said rails having 120 an extension, and means for releasably connecting said extension to the other rail, said means comprising a lug and a recess.
12. In a toy railway a pair of rails located end to end, and having alined chan-

- neled side faces, and means extending into said faces for releasably joining the rails together and for forming a spring joint.
13. In a toy railway a pair of wire rails located end to end, one of said rails having an extension forming with the other rail a releasable spring joint.
14. In a toy railway a pair of wire rails located end to end and each rail having opposed inwardly rolled faces, means secured to the rolled face of one rail and extending into the rolled face of the other rail for releasably connecting the same together.
15. In a toy railway a pair of wire rails having concave faces, and connecting means having a convex face extending thereinto.
16. In a toy railway, a cylindrical metal rail having a longitudinal side thereof pressed inwardly to increase the height of the rail.
17. In a toy railway, a wire rail having a longitudinal side thereof pressed inwardly to increase the height of the rail.
18. In a toy railway, a pair of spaced connected wire rails having spaced clamping members secured thereto.
19. In a toy railway, a pair of wire rails located end to end and having grooved faces, and means for releasably joining said rails to form a tension joint.
20. In a toy railway, a pair of rails located end to end and having grooved faces, one thereof having a sheet metal extension conforming to the shape of said grooved faces, and having the extended end portion constructed to yieldingly engage the grooved face of the adjacent rail when said pair of rails are joined together.
21. In a toy railway a wire rail having secured to an end thereof a sheet metal member projecting beyond the end of the rail.

Signed at Buffalo New York this 28th day of March 1923.

ALAN R. FERGUSSON.
